(57) **CLAIM**

The ornamental design for a wireless microphone set, as shown and described.

DESCRIPTION

FIG. 1 is a front, top perspective view of a wireless microphone set, showing my new design;

FIG. 2 is a front, top perspective view of a first element of the wireless microphone set;

FIG. 3 is a rear, bottom perspective view thereof;

FIG. 4 is a front elevation view thereof;

FIG. 5 is a rear elevation view thereof;

FIG. 6 is a left side elevation view thereof;

FIG. 7 is a right side elevation view thereof;

FIG. 8 is a top plan view thereof;

FIG. 9 is a bottom plan view thereof;

FIG. 10 is a front, top perspective view of a second element of the wireless microphone set;

FIG. 11 is a rear, bottom perspective view thereof;

FIG. 12 is a front elevation view thereof;

FIG. 13 is a rear elevation view thereof;

FIG. 14 is a left side elevation view thereof;

FIG. 15 is a right side elevation view thereof;

FIG. 16 is a top plan view thereof;

FIG. 17 is a bottom plan view thereof;

FIG. 18 is a front, top perspective view of a third element of the wireless microphone set;

FIG. 19 is a rear, bottom perspective view thereof;

FIG. 20 is a front elevation view thereof;

FIG. 21 is a rear elevation view thereof;

FIG. 22 is a left side elevation view thereof;

FIG. 23 is a right side elevation view thereof;

FIG. 24 is a top plan view thereof; and,

FIG. 25 is a bottom plan view thereof.

The broken lines in the figures illustrate portions of the wireless microphone set, that form no part of the claimed design.

1 Claim, 25 Drawing Sheets
